UNITED STATES PATENT OFFICE

JOHN HETHERINGTON, OF KEYPORT, NEW JERSEY

GAME DEVICE

Application filed December 2, 1932. Serial No. 645,356.

This invention relates to an amusement device and relates more particularly to a game combining skill and chance and provides a simple and interesting device operable under the action of moving spherical play-pieces commonly termed "marbles."

The game of marbles is played under varying rules or systems in different localities throughout the country. In most cases, however, it is the practice for the players to stand a relatively long distance from an objective and pitch the marbles in an attempt to reach or closely approach the objective. The objective may be a hole in the ground, a ring marked out on the ground or any indicated line or barrier.

It is an object of the present invention to provide a device to be used as an objective in a marble game to provide greater interest through the operation of mechanical means actuated by a moving marble.

Another object of the invention is to provide a device having an element movable upon contact with a moving marble to give indication of an act to be performed by a player.

Other objects and advantages of the invention will be apparent from the following description together with the accompanying drawing, in which

Fig. 1 is a top plan view of a device constructed in accordance with the present invention and showing a marble for movement toward the device, and

Fig. 2 is a view taken on line II-II in Fig. 1.

As illustrated, a preferred embodiment of the invention may comprise a base-plate 10. This plate may be in the form of a circular disc having a dome or convex surface and a peripheral flange 11. One side 12 of the flange serves as a supporting surface for the disc and the other side 13 as a face to receive characters as shown in Fig. 1 or other indicative inscriptions, the purpose of which will be presently explained.

Centrally disposed with respect to the base-plate is a pin 14 riveted at 15 to the plate and extending upwardly therefrom. The pin is provided with a shoulder to serve

as a bearing surface for a rotatable head or cap 16 disposed for rotation on the pin. Suitably secured to the pin is a member 17 having three arms, one of the arms 18 being shaped to serve as a pointer or indicator and so proportioned that the end of the pointer will move adjacent to the characters on the surface 13. The arms 19 and 20 also extend to the edge of the surface 13 but serve as contact members, the pointer also serving as a contact member. When a marble 21 is rolled up the surface of the base-plate it will strike one of the arms and cause the member 17 to rotate. The member is made to rotate freely and when it comes to rest the pointer will indicate a character as Put or Take or a number indicating that the player who delivered the marble is to perform an act in accordance with the rules of the game.

It is to be understood that the characters may be varied and that any desired set of numbers or legends may be used calling for acts to be performed by the players.

For the purpose of making the operation of the device more dependent on skill the base-plate is provided with barriers or obstructions. One set of these obstructions may consist of lugs or ears 21, 22 and 23 positioned ninety degrees apart on the outer edge of the dome portion of the plate 10. Another set may consist of similar lugs 24, 25 and 26 also disposed ninety degrees apart but in staggard relation to the first set of lugs and preferably in closer spaced relation to the center. The positions of the obstructions may be varied to make the game easier, or the obstructions may be increased in number to make the operation more difficult. The outer set of lugs are arranged with their edges in line with radial lines of the disc while the inner set of lugs are disposed transverse to the radial lines of the disc.

A marble traveling toward the arms of the member 17 if not properly directed will strike one of the outer lugs and be deflected in which case it will not strike the member 17. On the other hand the marble may pass the outer lug and strike an inner lug which

presents more area and again the result will be a failure to actuate the indicator member.

Furthermore the domelike formation of the disc serves to retard the movement of a marble as it travels toward the indicator and if the marble is not propelled with sufficient force it will lack energy to reach the pointer and will roll back off the disc.

In practice the device may be placed upon the ground or floor and the players each 10 donate any number of marbles in the "pot" or treasury. They then stand a given distance (about six paces) away and take turns in rolling a marble toward the indicator. 15 If the rolled marble hits the indicator the player must act according to the indication of the pointer when the spinner or member 17 comes to rest. If the pointer indicates Put the player donates the indicated number 20 of marbles and if Take is indicated the player wins the indicated number. The player then is permitted to shoot until he misses. The other players then shoot in 25 turn from their respective positions and depending on their skill in hitting the arrow and their luck as to the stopping position of the pointer they win or lose as the case may be. If desirable the final result may be determined by spinning the indicator 30 by hand which is accomplished by grasping the head 16 between the thumb and forefinger and rotating the member 17. The result is determined by the one scoring the highest total in two spins using the numbers 35 from 10 to 750 as provided on the surface 13. The one who scores highest may win all or part of the marbles left in the pot or treasury.

The above outline of rules is only given as 40 an example since it is obvious that the rules and regulations may vary to meet the de-

mands of the players in different localities.

A device constructed in accordance with the present invention makes it possible to bring into the game of marbles more interesting features which arouse more interest 70 in the exercise of skill combined with a reasonable amount of chance.

Although a preferred embodiment of the invention is shown and described herein it is to be understood that modifications may 75 be made therein without departing from the spirit and scope of the invention as set forth in the appended claims.

What is claimed is:

1. A marble game comprising a device 80 having a base-plate of dome shape, a rotatable member, means on the apex of said dome for rotatably mounting said member, arms on said member extending over said dome, said dome serving to divert the direction of a marble rolling toward said member. 85

2. A marble game comprising a device having a base-plate of dome shape, a rotatable member, means on the apex of said dome for rotatably mounting said member, 90 arms on said member extending over said dome, a flange extending from said dome to provide a face for characters and a support for the dome and said rotatable member. 95

3. A marble game comprising a device 100 having a base-plate of dome shape, a rotatable member, means on the apex of said dome for rotatably mounting said member, arms on said member extending over said dome, a flange extending from said dome to provide a face for characters, a support for the dome and said rotatable member and a plurality of obstructions on said dome to divert a moving marble from striking said arms. 105

JOHN HETHERINGTON.
